UNITED STATES PATENT OFFICE.

CHARLES L. GEBHARDT, OF GREEN, KANSAS.

GRAIN-SAVING ATTACHMENT FOR THRESHING-MACHINES.

1,382,901.

Specification of Letters Patent. Patented June 28, 1921.

Application filed September 8, 1920. Serial No. 408,994.

To all whom it may concern:

Be it known that I, CHARLES L. GEBHARDT, a citizen of the United States, residing at Green, in the county of Clay and 5 State of Kansas, have invented certain new and useful Improvements in Grain-Saving Attachments for Threshing-Machines, of which the following is a specification, reference being had to the accompanying drawings, which form a part hereof.

My invention relates to improvements in devices for the saving of grain in the process of threshing and the object of my improvements is to provide an attachment for 15 threshing machines of the ordinary type by means of which the grain is more completely separated from the chaff and returned to the machine.

I attain this object by means of the construction hereinafter described and illustrated in the accompanying drawings, in which—

Figure 1 is a side elevation in perspective of a grain thresher with my device attached; 25 Fig. 2, a sectional side elevation of that portion of a thresher to which my device is attached with a portion of my supplemental elevator boxing broken away;

Fig. 3, a detail view of the mechanism of 30 my invention with a section of the sieve broken away; and

Fig. 4, a vertical sectional view through the line $x-x$ of Fig. 3, of my invention as attached to the main thresher.

Similar reference numerals indicate like 35 parts throughout the several views.

1 refers to the main frame of the thresher to which my device is attached; 2, the elevator frame; 3, the fan-blades; 4, fan-pulley; 40 5, fan-shaft; 6, tilting wind-board; 7, wind-board tilting adjustment; 8, grain-auger; 9, sprocket operating such auger; 10, sprocket attached to fan-shaft; 11, sprocket on opposite end of shaft 26; 12, sprocket attached 45 to elevator shaft; 13, fan-door; 14, grain sieve; 15, grain-pan, its bottom sloping toward the auger 8; 16, chaff-auger to remove the waste from behind the fan-drum (this auger is unnecessary in the type of thresher in 50 which the blower may be placed on the outside of the machine); 17, sprocket operating such auger; 18, power sprocket connected by chain 19 with sprocket 17; 20, chain connecting sprockets 9 and 10; 21, chain con-

nected sprockets 11 and 12; 22, adjusting means for elevator-chain 23; 24, elevator-cups; 25, inside elevator-chain sprocket; 26, grain-conveyer shaft; 27, spout to elevator 2 through which the saved and separated grain is discharged into the tailings elevator 60 30; 28, fan-head; 29, thresher-shoe; 31, tail-board-of-the-shoe and 32, stacker-fan drum; 33, frame on which 14 rests.

My device is bolted to frame 1 so that the sieve 14, which is agitated by the thresher-shoe 29, receives the chaff or tailings from the tail-board of the shoe. The frame 33 of the sieve 14 extends rearward from and is attached to the rear of the tail-board-of-the-shoe 31 of the main machine by means of angle-irons secured to such thresher-shoe, one on each side, in which frame 33 rests and to which such angle-irons are secured. As such shoe is agitated in the process of threshing such sieve is also shaken. From 70 this chaff or waste the grain is separated by the blast from the fan 3 and falls to the grain-pan 15 and thence to the grain auger 8 by which it is conveyed to the tailings elevator by means of the supplemental elevator 2. It is operated by means of belt and pulley connected with the fanning-mill shaft of the thresher or other convenient power shaft.

The fan 3 extends across the thresher and 85 the wind-board 6 at the mouth of the blast channel is adjusted by any ordinary appliance for that purpose to provide such a size opening as the weight or density of the waste material may require. Such fan is operated 90 by means of a belt, from any convenient power, attached to pulley 4 and from the opposite end of shaft 5 a sprocket chain 20 connects sprocket-wheel 10 with sprocket-wheel 9, which in turn operates grain auger 8, 95 from which the power is transmitted to sprocket-wheel 11 connected by sprocket-chain 21 with sprocket-wheel 12 operating the elevator cups 24 by means of sprocket-chain 23 and discharging the cleaned or separated grain through spout 27 into the tailings elevator of the thresher.

In the ordinary process of threshing the unthreshed grain or rather the straw with the grain in the heads is thrown into the 105 feeder, from thence carried to the cylinder where much of the grain is separated from the heads and passes thence with the straw

through the beater to the straw-rack, where the loose grain falls to the grain-pan and the straw passes on to the blower.

In practically all threshers much of the poorly separated grain is returned to the cylinder and reseparated. Still the waste or chaff containing much unseparated grain, particularly when the machine is overfed, passes on over the end of the chaffer, and it is these tailings or waste, just before being caught by the blast from the stacker-fan, that my device catches, separates and carries to the tailings elevator, thereby saving the grain which would otherwise have passed out with the straw to the straw-stack.

Having thus described my invention what

I claim as new and desire to secure by Letters-Patent is,—

The combination with a threshing machine provided with a shoe having a tail-board, of a sieve attached to the rear of such tail-board and extending rearward therefrom and agitated by the movement of such shoe, such sieve being so disposed as to receive the tailings directly from such tail-board, a supplemental fan so disposed as to create an air blast upwardly through such sieve, and means for conveying the grain to a predetermined point.

CHARLES L. GEBHARDT.
